SWAB RELEASE MECHANISM

Filed Aug. 26, 1926

Inventor

Harvey R. Standlee

By Ralph S. Bassett

Attorney

UNITED STATES PATENT OFFICE.

HARVEY R. STANDLEE, OF TULSA, OKLAHOMA.

SWAB-RELEASE MECHANISM.

Application filed August 26, 1926. Serial No. 181,767.

The present invention relates to improvements in swabs utilized in connection with the production of crude oil.

The object of the present invention is to provide an attachment for a device of this character which will eliminate the possibility of injury to the well due to the over-loading of the wire line in instances where the swab is run too deeply, as the breaking of the wire line may cause the fixing of the swab in the casing with the result that it will be necessary to pull the casing to remove the same. By means of the present invention the swab continuously bleeds whereby the load reaches a predetermined weight that the wire line can pull.

Other features and objects will more clearly hereinafter appear by reference to the accompanying drawings, forming a part of this specification and wherein like numerals of reference designate corresponding parts throughout the several views, in which:

Figure 1 is a vertical sectional view of my present device in position on a swab.

Figure 2 is a similar view of the valve mechanism taken through the valve at right angles to Figure 1.

Figure 3 is a bottom plan view, and

Figure 4 is a transverse section on line 4—4 of Figure 2.

Referring to Figure 1, the swab is indicated by the reference character A and is provided with the usual central tubular conduit a threaded at its lower end to receive the upper threaded portion 1 of the over-load valve assembly.

This valve assembly includes a casing tubular in character and comprising upper section 2 and lower section 3. The reduced threaded portion 4 of the section 3 is threaded into the lower threaded portion 5 of the upper section 2. The upper threaded portion 1 of the assembly is reduced in diameter adjacent its extremity and the lower portion of the assembly is similarly constructed and is threaded internally as at 6 for any necessary connection.

The inner upper face 7 of the reduced portion 4 of the lower valve casing section is beveled inwardly at an angle of 45° to form an annular valve seat for the reception of a valve 8 hereinafter described.

The valve assembly includes in addition to the casing, the downwardly seating valve 8 and the upwardly seating valve 9, the latter

seating against the valve seat 10 formed on the inner face of the downwardly seating valve 8. This valve 8 is in annular form and is provided with the two faces, the valve seat 10 heretofore mentioned and the valve face 11 which seats against the valve seat 7 formed on the inner face of the reduced portion 4. The valve 9 closes the opening formed, due to the annular structure of the valve 8. This valve 9 is secured to the valve stem 12, the upper and lower extremities of which extend and slide through central perforations formed through the integral web portions 14 and 15 of the casing sections 2 and 3, respectively. These web portions 14 and 15 are located inwardly from and adjacent to the reduced portions of the casing sections. For centering the valve 8 with respect to the valve 9, the former is provided with the transverse web 16 enlarged centrally at 17 to accommodate the central opening 18, through which the stem passes. The valve 8 is provided with the diametrically opposite guide flanges 19 which extend upwardly from the valve body at points flush with the inner adjacent edge of the valve seat 10. An upwardly extending circular guide flange 20 is formed immediately adjacent the opening for the valve stem. A screen 21 of tubular form is arranged so that its lower opened end snugly engages the outer face of the flange 19. This screen is partially closed at its upper end by means of the integral cap 21^a formed with a central opening through which the valve stem 12 passes. The valve stem adjacent this opening in the cap 21^a is screw threaded to accommodate the lock nut 22 which acts as a stop to limit the upward movement of the screen. This screen is normally under tension by means of the spiral spring 23, the lower end of which is positioned between the adjacent walls of the flanges 19 and 20 and the upper end of which is positioned by means of the downwardly extending flange 23 formed integral with the cap 21^a adjacent the central opening therein.

In use, the upper end of the assembly will be positioned on the lower end of the tubular conduit of a swab. An operator can then run the swab into the well and the valves 8 and 9 will move upwardly, permitting the passage of the fluid through and above the swab. In the event that the swab is run too great a distance into the well, so that the amount of fluid located above the swab is

too great weight for the strength of the supporting wire line, then in that event the valve 9 will become unseated under the excess weight and the fluid will pass there-through and back into the well. The estimated weight of material for releasing the valve 9 can be determined and regulated by means of the lock nut 22, the adjustment of which will vary the tension of the spring 23, 10 against the tension of which the valve 9 opens. Attention is directed to the fact that by virtue of the novel arrangement and construction of the valve members 8 and 9, the entire passage through the casing is 15 opened when the swab is being lowered into the well. This arrangement eliminates any retarding effect on the movement of the swab and permits the usual rapid movement of same.

20 The provision of the screen 21 which surrounds the spring, prevents rubber or other foreign material, which might be in the oil from going through the relief valve seat and thus causing the valve to stand open. The 25 two valves and the screen are kept in alignment and positioned with relation to each other by the means heretofore mentioned. The screen is kept open and clean by the

passage of the fluid when lowering the swab into the well. 30

The present invention may readily be adapted for use in any instance where a relief valve is essential.

Having thus described my invention, what I claim as new and useful and desire to secure by Letters Patent is:

A swab unloader, comprising a tubular casing having a stationary valve seat therein, a reciprocating rod arranged within the casing and guided by the latter, a main valve loosely 40 mounted on the rod and engageable with said seat, said valve having an opening there-through and a valve seat, an auxiliary valve fixed on the rod and engageable with the last mentioned seat, a nut adjustably mounted on 45 said rod, an annular screen surrounding the rod and slidably engaging the main valve, a cap at one end of the screen engaging said nut, and a coiled spring arranged within the screen and having one of its ends engaging 50 said cap and its other end engaging the main valve, for normally holding the auxiliary valve in closed position.

In testimony whereof I affix my signature.

HARVEY R. STANDLEE.
